UNITED STATES PATENT OFFICE

2,369,918

PREPARATION OF PROVITAMINS

Hans R. Rosenberg, Wilmington, Del., assignor to
 E. I. du Pont de Nemours & Company, Wil-
 mington, Del., a corporation of Delaware

No Drawing. Application April 16, 1942.
 Serial No. 439,241

4 Claims. (Cl. 260—397.2)

This invention relates to the preparation of organic compounds containing a cyclo-pentano-perhydro-phenanthrene nucleus. More particularly it relates to the preparation of such compounds from Δ^5 -7-hydroxy-steroid esters by the removal of acid groups therefrom. In one of its preferred embodiments, it relates to the preparation of 7-dehydro sterol monocarboxylic acid esters and 7-dehydro sterols from Δ^5 -7-hydroxy-sterol monocarboxylic acid esters by the removal of monocarboxylic acid groups therefrom. The invention also relates to novel procedural conditions for preparing such 7-dehydro steroid compounds.

The thermal decomposition of diesters of 7-hydroxy-sterols and monocarboxylic acids, at reduced pressures has been described in U. S. P. 2,098,984. Under the conditions specified therein small yields of 7-dehydro-sterol esters are formed. The 7-dehydro-sterol esters are then saponified to remove the remaining acid groups. 7-dehydro-sterol esters may be prepared from such diesters of steroids by the procedure of U. S. P. 2,209,934 involving treatment with organic nitrogenous bases such as organic amines until an acid group has been removed. The 7-dehydro esters may then be reacted with a saponifying agent to yield 7-dehydro sterols. The use of oxonium salt forming compounds in the place of all or part of such bases with or without additional assisting agents in addition has been described in U. S. P. 2,255,815.

While the above-described processes have commercial utility certain of them have some shortcomings from the standpoint of a practical easily controllable process. The thermal decomposition at elevated temperatures and under reduced pressure require very careful supervision. The maintenance of a high degree of vacuum interposes economic and practical difficulties of operation. In addition, the heating of the ester melt causes decomposition of useful products into those of no economic value. Organic nitrogen bases and oxonium salt forming compounds have utility, but are somewhat expensive and are sometimes difficult to obtain.

An object of this invention is to provide new and useful processes for removing acid groups from organic esters containing a cyclo-pentano-perhydro-phenanthrene nucleus. A further object is to provide processes for making 7-dehydro steroid compounds which can be carried out at moderate temperatures. A still further object is to provide processes for making 7-dehydro sterol esters in which uneconomic by-product formation

is avoided. Another object is to provide new processes for making 7-dehydro steroids in which available or easily obtainable and economical agents can be used. A further object is to provide processes for making 7-dehydro-steroids from esterified 7-hydroxy-steroids which can be carried out in simple and economical apparatus. Still other objects will be apparent from the following description of the invention.

10 It has now been found that acid groups can be removed from esterified organic compounds containing a cyclopentano-perhydro-phenanthrene nucleus by heating them in the presence of an organic cyanic acid compound such as a nitrile or an equivalent compound.

In a more limited sense the invention involves heating Δ^5 -7-hydroxy-steroid esters of monocarboxylic acids in a liquid medium in the presence of a substantial amount of an organic nitrile.

20 According to a more preferred aspect of the invention the above objects are accomplished by heating Δ^5 -7-hydroxy steroid esters in a liquid medium with a substantial proportion of a liquid nitrile until a material amount of acid groups 25 has been split from the 7:8-position of ring II of such steroid esters. The 7-dehydrosteroid compounds may then be further purified and/or processed.

20 In a preferred aspect of the invention a diester of a 7-hydroxy sterol and a monobasic organic carboxylic acid is heated to a temperature between 50° C. and 300° C. with at least one half a molecular equivalent of a nitrile in a liquid medium for a period of at least one hour. In 35 the event the nitrile chosen is a liquid at the temperature employed or can be liquefied by increased pressure, it is unnecessary to provide a further liquid medium.

The nitriles used in accordance with the teachings hereof should not have a deleterious action during the process. To be more specific they should be nondestructive of Δ^5 -7-hydroxy steroid esters. In order to determine if the particular nitrile or cyanate compound will not be destructive of such steroid compounds, the following test 45 may be carried out:

Test for destructive properties

Two milligrams of ergosterol or ergosterol acetate are heated in the presence of the nitrile or cyanate compound to be tested and heated in a sealed tube to a temperature of 200° C. for one hour. The reaction product is then diluted with ethyl alcohol and spectroscopically examined for 55 the presence of ergosterol bands. The compound

in question is suitable if the ergosterol is not destroyed. If desired, cyclohexane may be also used as a diluent in the test.

The invention will be further illustrated but is not intended to be limited by the following examples wherein the parts stated are parts by weight.

Example I

Five parts of 7-hydroxy-cholesterol-dibenzoate were dissolved in fifty parts of benzonitrile and heated to reflux in nitrogen atmosphere over a period of eight hours. After cooling, the reaction product was taken up in ether and the ether solution washed with an aqueous sodium carbonate solution and dried over sodium sulfate. The ether was then distilled off and the benzonitrile removed by distillation in vacuo. The residue was crystallized from acetone. 2.3 parts of 1-dehydro-cholesterol-benzoate corresponding to a yield of 57.5% was obtained.

Example II

Five parts of 7-hydroxy-cholesterol-dibenzoate were dissolved in thirty parts of phenyl-isothiocyanate and heated to reflux for two hours. The phenyl-isothiocyanate was then distilled off under vacuum and acetone was added to the residue. Upon cooling, 0.52 part of 7-dehydro-cholesterol-benzoate crystallized out. This corresponds to a yield of 12% of theory.

It should be understood that the invention is not limited to the treatment of the specific 7-hydroxy-sterol esters described in the working examples. On the contrary, it embraces the treatment of steroids generally wherein a double bond exists in a position adjacent to the esterified hydroxy group in the 7-position regardless of whether additional substituents are also present in other positions in the molecule. Any ester compounds having the cyclo-pentano-perhydro-phenanthrene skeleton may be used wherein the ester group is in the 7-position and a double bond in the 5,6-position. Such substances are sometimes termed steroid or sterid compounds and include those having the nucleus referred to with or without side chains including said chains with other functional groups such as oxo, hydroxyl and carboxyl groups and their derivatives. Thus, the term "steroids" includes not only sterols, but also bile acids, plant heart poisons, saponines and sex hormones. Among the suitable polyesters of the above-described types are esters of 7-hydroxy-cholesterol, e. g., 7-hydroxy-cholesterol diacetate, 7-hydroxy cholesterol di(nitrobenzoate); 7-hydroxy-sitosteryl diesters, e. g., 7-hydroxy sitosterol dibenzoate, 7-hydroxy-sitosterol di(nitrobenzoate), etc.; 7-hydroxy stigmasterol diesters, e. g., the dibenzoate, diacetate, etc.; 3,7-dihydroxy-5-cholenic acid esters, Δ^5 -androstetriol-3,7,17-triesters, and the corresponding esters of pregnane series. Still other suitable esters include the simple or mixed carboxylic esters of 7-hydroxy sterol compounds obtainable from acids such as nitrobenzoic, m-dinitrobenzoic, chlorobenzoic, toluic, phenyl-acetic, cinnamic, formic, acetic, propionic, butyric, valeric, etc. acids and their acid anhydrides and acid halides, e. g., acyl chlorides. Any of the diesters disclosed in U. S. Patents Nos. 2,209,923 and 2,215,727, for instance, may be used as starting materials in the present processes.

The amount of organic nitrile or cyanate can be varied over a fairly wide range. In general, it is advisable to have about an equimolar proportion of such compound based on the steroid

treated present during the acid splitting reaction. From 1 to 100 parts of nitrile or cyanate compound per part of steroid ester, for example, represents a practical range, and from 5 to 25 parts a preferred range. An excess of the nitrile or cyanate compound in general renders the process more practical and results in higher yields.

The temperature and time may also be varied over a fairly wide range, e. g., from 150° C. and less to 300° C. and over. A temperature from 160° C. to 260° C. represents a preferred range. The time may vary from about 2 hours to 16 hours and over depending somewhat on the temperatures employed. For example, 2 hours' heating at 220° C., 6 hours at 200° C., and 16 hours at 180° C. give substantially the same yields. It is not necessary, however, to convert all the diester to the 7-dehydro compound. The reaction may be cut short when partially complete. In place of the specific nitriles set forth in the working examples may be substituted methyl cyanide, ethyl cyanide, cetyl cyanide, phenylacetic acid nitrile. Organic cyanic acid compounds which are equivalents of nitriles can be used. These nitriles can be used with any of the steroid esters specifically mentioned or falling within the above definitions. Mixtures of two or more of such compounds can be used.

Similarly, in place of the particular cyanate compounds of the examples may be substituted benzyl isothiocyanate, cyclo-hexylisothiocyanate, butyl-isothiocyanate, hexyl-isothiocyanate, phenyl-thiocyanate, benzyl-thiocyanate.

The new procedures hereof represent a distinct contribution to the art. The use of the nitriles for acid splitting of steroid esters to form 7-dehydro compounds is of special utility. The invention provides a new use for organic nitriles, isocyanates, thiocyanates, and isothiocyanates. The compounds enable the acid splitting reaction to be carried out at lower temperatures with attendant advantages.

As many apparently widely different embodiments of this invention may be made without departing from the spirit and scope thereof, it is to be understood that the invention is not to be limited except as defined by the appended claims.

I claim:

1. The process which comprises heating the diester of a 7-hydroxy sterol and an organic monobasic carboxylic acid with a liquid organic nitrile selected from the class consisting of benzonitrile, methyl cyanide, ethyl cyanide and phenylacetic acid nitrile, to a temperature between 100° C. and 300° C. for a period of at least one hour, and recovering therefrom a 7-dehydro sterol compound.

2. The process which comprises heating the diester of a 7-hydroxy sterol and an organic monobasic carboxylic acid with benzonitrile to a temperature between 100° C. and 300° C. for a period of at least one hour, and recovering therefrom a 7-dehydro sterol compound.

3. The process which comprises heating the diester of 7-hydroxy cholesterol and an organic monobasic carboxylic acid with benzonitrile to a temperature between 100° C. and 300° C. for a period of at least one hour, and recovering therefrom a 7-dehydro sterol compound.

4. The process which comprises refluxing 7-hydroxy-cholesterol-dibenzoate and benzonitrile in an atmosphere of nitrogen for a period of about 8 hours, and recovering therefrom a 7-dehydro sterol compound.
